UNITED STATES PATENT OFFICE.

GEORGE M. DAVIDSON, OF CHICAGO, ILLINOIS.

WATER-PURIFIER.

SPECIFICATION forming part of Letters Patent No. 729,286, dated May 26, 1903.

Application filed January 31, 1903. Serial No. 141,295. (No model.)

To all whom it may concern:

Be it known that I, GEORGE M. DAVIDSON, a citizen of the United States, residing at Chicago, in the county of Cook and State of Illinois, have invented certain new and useful Improvements in Water-Purifiers, of which the following is a specification.

This invention relates to that class of mechanisms known as "water-purifiers"—that is, apparatus or mechanism arranged to mix predetermined quantities or proportions of chemicals with feed-water preliminary to the feeding of the same into a steam-boiler, so as to minimize as much as possible the deleterious action of ordinary waters on the boiler-shell during the generation of steam—all of which will more fully hereinafter appear.

The principal object of the invention is to provide a simple, economical, and efficient water-purifier.

Other and further objects of the invention will appear from an examination of the drawings and the following description and claims.

The invention consists principally in the combination of a chemical-feed tank, stirring mechanism movably mounted therein, pump mechanism secured to and connected with the feed-tank inside the mixing-chamber, a water-supply pipe arranged to receive the chemical-supply as it passes from the pumping mechanism in the chemical-feed tank, and a tilting vessel arranged to receive the discharge of the mixed chemical and water supply and connected with the pumping mechanism to operate the same by and during its movements.

The invention consists, further and finally, in the features, combinations, and details of construction hereinafter described and claimed.

In the accompanying drawings, Figure 1 is a plan view of a water-purifier constructed in accordance with these improvements looking at it from above; Fig. 2, a cross-sectional elevation taken on line 2 of Fig. 1 looking in the direction of the arrow; Fig. 3, a front elevation of a complete mechanism constructed in accordance with these improvements; Fig. 4, an enlarged vertical sectional elevation of the liquid-level-indicating mechanism, showing it attached to the inner side of the chemical-feed tank, taken on line 4 of Fig. 1 look-

ing in the direction of the arrow; and Fig. 5, a sectional elevation of the pumping mechanism, showing it attached to the inner side 55 of the mixing-chamber of the chemical-feed tank, taken on line 5 of Fig. 1 looking in the direction of the arrow.

In the art to which this invention relates it is well known that all natural boiler-feed waters contain more or less incrusting solid or other deleterious matter which if fed into the steam-boilers is during the generation of steam deposited in the form of scale on the inner surface thereof, all of which acts to incrust the flues and sheets, and thereby to lessen the efficiency of the boiler, as well as resulting in extra consumption of fuel and decrease in the life of the boiler. It is also well known that a great many chemicals may be 60 used and mixed with the feed-water before it enters the boiler to precipitate and remove said solids or other deleterious substances, so that the water when used will not have the objectionable actions above noted on the boiler. 70

The principal object, therefore, of this invention is to provide a suitable mixing apparatus, one which measures the chemicals and water in predetermined quantities and thoroughly mixes them before they enter a settling tank or tanks preliminary to being fed into the boiler, and means in the settling-tanks for thoroughly agitating the purified water and sediment therein, so as to obtain the best results, all of which will more fully 85 hereinafter appear.

In constructing and arranging an apparatus in accordance with these improvements I provide a preliminary chemical-mixing tank *a* of the desired size and shape, preferably 90 cylindrical in contour, and place it in a vertical position, as shown particularly in Fig. 2 of the drawings. This preliminary chemical-mixing tank is, as above suggested, provided for the purpose of preliminarily mixing 95 the chemicals with the desired quantity of water in order to primarily dissolve and mix them and is provided with a screen *b*, which acts as a strainer to separate the liquid from the coarse solid elements, so that the mixed 100 chemicals and water may be drawn off through a pipe *c*, which I will hereinafter term the "chemical-supply" pipe. In order to thoroughly mix this chemical solution after it has

been primarily dissolved or mixed with the requisite amount of water, a chemical mixing and feed tank *d* is provided, which is made, preferably, oval in shape, vertically arranged, 5 and open at the top, into which the chemical-supply pipe *c* discharges. This chemical-supply pipe, as shown in the drawings, is provided with a plug-valve *e*, which may be opened and closed whenever desired or necessary—that is, whenever it is desirable to supply the chemical mixing and feed tank with a fresh supply of chemicals the plug-valve is opened and whenever it is necessary to shut off such supply the plug-valve is closed, all 10 of which will be understood and appreciated by those conversant with the art.

To thoroughly mix and keep the chemical solution stirred and in condition for use in the chemical-feed tank above described, stirrers or beaters *f* are provided, mounted upon a vertical shaft *g*, in turn rotatably mounted in the axial center of such feed-tank. The lower part of this rotatable stirrer-shaft has a stepped bearing *h* in the lower or bottom 20 part of the chemical-feed tank, and the upper part is rotatably mounted in a bracket *i*, in turn mounted upon cross-bars 10 on the upper part of the tank. The lower part is separated from the upper part by means of a 25 wire mesh or screen *j*, which serves to strain the liquid and keep the coarse solids above the same and also, as hereinafter set forth, to permit nothing but liquid or the finest solids from passing out of the tank.

35 In order to measure and feed the chemical solution so that it may be mixed with the requisite quantity of water-supply, the chemical-feed tank is provided with two pumps *k*, arranged inside thereof, so as to have their 40 open lower ends at all times below the water-level and in the mixing-chamber of such tanks. These pumps, as will be seen from an examination of the drawings, are vertically arranged and are formed in two tubular sections—a lower smaller section *k'* and an upper relatively larger section. The lower tubular sections are, as above suggested, open at their lower ends and in the chemical-feed tank below the liquid-level, and in order to 45 facilitate the cleaning of the pumps a ball-valve is formed by a removable cage *l*, having a tapered engagement with the tube of the pump and provided with a ball-valve *m*. By this arrangement it will be seen that when 50 the suction mechanism, hereinafter described, is removed the operator may take a hook and pass it beneath the loop *m'* of the cage and remove the same upward and out of the tubular section for purposes of repair or 55 renewal. By making a pump in two tubular sections with the larger diameter at the top the suction or plunger mechanism *o*, which is made in the shape of a cage with a ball-valve *p* therein, may be fitted to the lower 60 and relatively smaller section, so as to reciprocate therein, and when necessary may be drawn upward therefrom. As it does not fit

the upper tubular section, it will also be seen that it may be drawn easily and readily out through the same for purposes of renewal or 70 repair. It is further clear that no incrustation of chemicals is likely to take place within the pump, for the reason that the pump being at all times arranged within the liquid-chamber of the chemical-feed tank the sediment will either become dissolved or fall backwardly and downwardly into the bottom of the tank, thus preventing any clogging of the pumping mechanism. The pumps are provided with discharge-spouts *q* at or near their 75 upper portions which lead to and discharge into an open duct or ducts *r*, having a single discharge-spout *s*, arranged above a water-supply pipe *t*. This water-supply pipe is provided with a funnel *u*, arranged, as shown 80 particularly in Figs 1 and 2, directly underneath the single discharge-spout of the open channels or duct, so that before the water passes out of such water-supply pipe the chemicals are fed therein for the purpose of 85 being thoroughly mixed with the water and in the requisite quantities. By this arrangement the open duct or channel minimizes the danger of clogging which is apt to take place in a closed pipe or tube from the incrustation of the solids therein, and if any incrustation should take place it can be readily removed by the operator as desirable or necessary. It is desirable that these quantities of 90 chemicals and water be measured with some care and mixed in the required proportions in order to obtain the desired results, and also that it be done as economically as possible. To accomplish this result, a tilting measuring vessel *u* is provided and mounted upon a 95 pivot *v*, in turn rotatably supported on pillow-blocks *w* directly under the discharge of the mixed water and chemicals as they leave the water-supply pipe, so that it may be tilted from side to side. This tilting and measuring 100 vessel is provided with two measuring-chambers *u'* and *u''*, so that when it is in the position shown in Fig. 3 the mixed water and chemicals may flow into the chamber *u'* until it is nearly filled. When such chamber is 105 nearly filled, it counterbalances the weight of the other end of the tilting vessel, depresses it, and at the same time raises the other, so that the water may flow out and over the edge thereof and into the desired conduit or 110 vessel for purposes of storage or otherwise. While the chamber *u'* is emptying the chamber *u''* is being filled, and when the latter is 115 filled it in turn is depressed, returning the opposite end of the tilting vessel to the position shown in Fig. 3. These chambers are of 120 a predetermined size, which is best reached by determining the quantities of water and chemicals that should be mixed, and during their tilting operations operate, by means of 125 the mechanisms hereinafter described, the pumping and stirring mechanism, thereby feeding the desired amount of chemicals into 130 the water-supply and during the operations

of the vessel only. In order to operate the pumps during the tilting operations of the measuring vessel, the rods of the pump-plungers are connected to a walking-beam *y*, which 5 has its sleeve portion vibrantly mounted on a shaft *z*. The ends of this walking-beam are connected, by means of chains 11 and 12, with clevises 13 and 14, respectively, on each end of the tilting vessel. An examination of 10 Fig. 3 of the drawings will show that when the parts are in the position shown therein and as the vessel is being tilted downwardly and to the left the pump *k* at the right of such figure is operated, or the plunger thereof, so as to furnish a predetermined quantity 15 of mixed chemical to the water-supply pipe. It will be understood that the water-supply is constantly running and that the pump is intermittently acted and only during the 20 tilting operations of the tilting vessel. From this description of construction and operation it will be seen that a certain predetermined quantity of chemicals is fed to each side of the measuring vessel in proportion to the 25 amount of other liquid which it will take to fill the same. In other words, the water-supply is constant and the tilting operations and chemical supply intermittent.

It is desirable to provide means for automatically rotating the beater-shaft *g*. To accomplish this, the horizontal shaft *z*, above set forth, is provided with a bevel-gear 15, meshing with a bevel-pinion 16 on the upper end of the beater-shaft. The outer end of the 30 horizontal shaft is provided with a sprocket-wheel 17, around which a chain 18 passes, the ends of such chain being connected to the clevises 13 and 14, respectively, by means of pieces of ordinary chain 19 and 20. By 35 this construction and arrangement it will be seen that as the tilting vessel is operated it causes the beater-shaft to rotate and the beaters thereon to operate and thoroughly agitate and assist in dissolving and mixing 40 the chemicals in the chemical-feed tank. It is also desirable to have some means by which the level of the liquids in the chemical-feed tank may be easily determined. For this purpose a stand-pipe 21 is arranged within the 45 chemical-feed tank (see Fig. 4) and open at its upper and lower ends. In this stand-pipe

is arranged an empty bottle or similar vessel 22', provided with a rod 22, extending upwardly therefrom and out through the upper end of the tank. This rod may have a cord 55 or cable 23 attached thereto and passed over idlers 24 and 25 and down into any desired position; so as to operate any desired indicator, and thus inform the operator as to the level of the liquid in the tank without any 60 necessity of the operator inspecting the interior to ascertain what liquid may be therein.

Buffer-springs 26 are provided and arranged underneath each end of the tilting vessel, so as to lessen or absorb the shocks or jars incident to the stopping of the tilting vessel as it approaches each limit of its motion.

I claim—

1. In a water-purifier of the class described, the combination of an elongated chemical-feed tank, stirring mechanism mounted therein, a plurality of pump mechanisms secured to the walls of such feed-tank and inside the mixing-chamber, a water-supply pipe, open ducts or channels leading from the pumping 70 mechanism in the chemical-supply tank so as to discharge the chemical-supply into the water-supply tank, and a tilting vessel arranged to receive the discharge of the mixed chemical and water supply and connected 75 with the pumping mechanism so as to operate the same, substantially as described.

2. In a water-purifier of the class described, the combination of an oval chemical-feed tank, stirring mechanism mounted in such 85 chemical-feed tank, two pumps vertically arranged inside of such chemical-feed tank secured to the walls thereof and open at their bottom portions, a water-supply pipe, an open channel or duct leading from both of the 90 pumps to the water-supply pipe so as to discharge the chemical-supply therein, and a tilting vessel arranged to receive the discharge of the mixed chemical and water supply and connected with the pumping mechanism 95 so as to operate the same, substantially as described.

GEORGE M. DAVIDSON.
